UNITED STATES PATENT OFFICE.

OLIVER E. J. BRUBAKER AND GEORGE MOTES, OF RARDEN, OHIO.

MAIL-BAG DELIVERING AND RECEIVING DEVICE.

1,150,167.

Specification of Letters Patent.

Patented Aug. 17, 1915.

Application filed August 6, 1914. Serial No. 855,445.

To all whom it may concern:

Be it known that we, OLIVER E. J. BRUBAKER and GEORGE MOTES, citizens of the United States, residing at Rarden, in the county of Scioto and State of Ohio, have invented certain new and useful Improvements in Mail-Bag Delivering and Receiving Devices; and we do declare the following to be a full, clear, and exact description of the invention, such as will enable others skilled in the art to which it appertains to make and use the same.

This invention relates to improvements in devices for simultaneously delivering and receiving mail sacks and the like and has for its main object to provide a device of this character which may be simply and inexpensively constructed yet one which will be highly efficient in operation.

In carrying out the above end, independent mail receiving and delivering mechanisms are employed on the mail coach and at points along the railway, the mechanism employed at the last mentioned positions comprising a flexible track which extends longitudinally of the railway and which is supported intermediate its ends by an arm projecting laterally from an upright post, a carriage having grooved rollers mounted upon said track, a receiving arm pivoted to said carriage, still another arm projecting from said post above the receiving arm and coacting bag devices on said last mentioned arm and the arm spaced above the same, for suspending a mail bag therebetween.

A further object of the invention is to so construct the carriage and the parts carried thereby as to allow the suspended bag to act as means for retaining the pivoted receiving arm in horizontal or operative position, this construction allowing said receiving arm to drop by gravity when the bag supporting the same has been removed.

A further object of the invention is to so position one of the rollers of the carriage as to cause the same to coact with a plate to be described for the purpose of preventing said carriage from tilting when the parts are in operative position.

With these objects in view, the invention resides in certain novel features of construction and combination herein described and claimed and shown in the drawings wherein:

Figure 1 is a perspective view of a portion of a mail coach, the parts carried there-

by, and the coacting parts positioned to one side of the railway; Figs. 2 and 3 are respectively a side elevation and a plan view of the parts shown in Fig. 1 and illustrating more particularly the mounting of the track to be described; Fig. 4 is a vertical transverse section taken on the line 4—4 of Fig. 3, showing in full lines, the position of parts when supporting a sack and illustrating in dotted lines, the position of the receiving member when a sack has been delivered thereto; and Fig. 5 is an enlarged vertical section taken on the line 5—5 of Fig. 4 with the parts in the position shown in dotted lines, in said figure.

In the accompanying drawings, a mail car C is illustrated having the usual doorway D which is usually equipped with a mail catching arm A, the latter being here shown as of substantially fork shape and as mounted upon a rock shaft S, the latter being provided with an inwardly extending operating handle H by means of which the arm A may be thrown to its outer or operative position or to its inner or inoperative position. The arm A is provided at a suitable point with a longitudinally projecting finger 1 which is adapted to receive one of the rings 2 carried by the opposite ends of a mail bag 3, the ring at the opposite end of said bag being adapted to surround a second finger 4 which lies directly beneath the finger 1 and which is carried upon a downwardly and outwardly curved arm 5, the upper end of said arm being secured to a shaft 6 lying parallel to the shaft S, said shaft 6 being rotatably mounted in bearings 7 carried by one side of the car C adjacent the doorway D and being normally rocked to swing the arm 5 inwardly, by a coil spring 8 which is secured at its opposite ends to the frame of the doorway D and to an arm 9 which extends inwardly from said shaft 6. It will be noted that the shaft 6 projects only a small distance into the doorway D.

The construction so far described, constitutes the above mentioned means for delivering a mail bag from the coach C and for receiving a bag from the mechanism now to be described which is placed adjacent the railway.

Positioned a suitable distance to one side of the railway are a pair of upright posts 10 and an intermediate post 11 which is located nearer to the track than are the posts

10, as clearly seen in Fig. 3. The post 11 is provided with an arm 12 which projects laterally therefrom toward the railway, the free end of said arm 12 receiving upon its 5 upper surface, a plate 13 which projects longitudinally therefrom, said plate having its free end bowed upwardly and inwardly as at 14 to provide a transverse loop as most clearly seen in Fig. 4, this loop embracing 10 the intermediate portion of a cable 15 which constitutes a track whose opposite ends are united at 16 to the upper ends of the posts 10 at points spaced considerably above the arm 12.

15. Mounted for movement upon the cable 15 is a carriage 17 which preferably comprises a casing formed of a single metal plate 18 which is bent substantially upon itself at 19, this bend constituting the upper end of the 20 casing from which one free end of the plate depends as indicated at 20 and is formed into pivot loops or knuckles 21 from which said free end rises at 22 in spaced relation to the upright portion 20, a pair of cylindrical rollers 23 being located between the portions 20 and 22, said rollers normally underlying the track 15 while a pair of grooved rollers 24 are revolvably mounted between the upper end of the portion 20 and the opposite 30 end portion 25 of the plate 18 which depends from the bend 19 and lies parallel to said portion 19, said grooved rollers 24 riding upon the cable or track 15 as clearly seen in the drawings. It may here be explained, 35 that the rollers 23 may be allowed to contact with the under side of the plate 13 when the device is in operative position, thus preventing the carriage 17 from tilting upon the track.

40. Spaced toward the railway from the carriage 17, is a substantially T-shaped block 26 to whose shank a pair of forked receiving arms 27 are secured, said arms projecting in opposite directions. As clearly seen in the 45 various figures of the drawings, the head of the T-shaped block 26 is provided with a pair of lugs 28 which straddle the knuckles 21, a suitable pivot pin or bolt 29 being passed through said knuckle and said ears 50 whereby the arms 27 are pivotally connected with the carriage 17. The block 26 is also provided with a laterally extending finger 30 which is preferably provided with an upright shank 31, the latter being threaded 55 through the block 26 and a boss formed on the upper side thereof and receiving a nut 32 on its lower end. It may here be explained that the arms 27 are positioned in the plane in which the center or contracted 60 portion of the bag 3 is located, thereby allowing one of said arms to receive said bag as the coach C moves past the mechanism supported at the side of the railway.

65. Projecting toward the railway from the central post 11 and preferably lying parallel

to the arm 12 is still another arm 33 whose free end carries a finger 34 lying directly above the finger 30 previously described, said fingers 30 and 34 being adapted to be encircled by the rings 35 of a bag 36 to be 70 taken up by the coach. The bag 36, when thus supported, is so positioned as to allow the arm A carried by the coach C, to engage its central portion whereby the sack 36 will be taken from the crane by the passing 75 coach, thereby simultaneously receiving and delivering the pair of bags.

From the foregoing description, taken in connection with the accompanying drawings, it will be seen that the bag 36 supports 80 the receiving arms 27 in operative position and that said arms 27 are allowed to fall to the dotted line position shown in Fig. 4 when said bag 36 is removed by the mechanism of the coach. Before descending however, one of the arms 27 receives the mail bag 3 from said coach, the momentum of said bag 3 now causing the carriage 17 and the arms 27 to travel up one of the inclined ends of the cable 15, thus gradually checking 95 the momentum and bringing the delivered sack and its carrying means to a standstill.

As hereinbefore suggested, and as clearly seen in Fig. 4, the rollers 23 may be positioned directly beneath the plate 13 when the parts stand in the position seen in this figure, thus absolutely preventing the carriage 17 from tilting upon its flexible track or cable 15.

We have described and illustrated two arms 27 but it will be clear that but one of these arms becomes active when the coach is traveling in one direction while the opposite arm may be employed for a railway having a single track only, in which case it becomes necessary for the coaches to run in opposite directions upon the same track.

We may here explain that by pivotally connecting the arms 27 with the carriage 17, the weight of said arms pulling normally downward upon the sack 36 suspends the same in a normally stretched condition to be readily engaged by the arm A.

By a careful inspection of the disclosures made in the accompanying illustrations in connection with the preceding description and explanation, it is thought that the construction and operation of the device will be readily understood.

Having thus described our invention, what we claim as new and desire to secure by Letters Patent is:—

1. A combined bag receiving and delivering device comprising a track located to one 125 side of and extending longitudinally of a railway, a carriage on said track, a bag receiving arm pivoted to said carriage and projecting toward the railway, a support spaced above said catching arm, and inde- 130

pendent bag holding devices on said arm and said support for suspending a mail bag therebetween.

2. A combined bag receiving and delivering device comprising a track located to one side of and extending longitudinally of a railway, a carriage on said track, a block pivoted to said carriage, a bag receiving arm carried by said block, a support above said 10 arm, and independent bag holding devices on said receiving arm and said support for suspending a mail bag therebetween.

3. A combined bag receiving and delivering device comprising a track located to 15 one side of and extending longitudinally of a railway, a carriage having supporting rollers revoluble upon said track, said carriage having a pivot knuckle, a block spaced toward the railway from said carriage, an 20 ear formed on said block and pivoted to said knuckle, a bag receiving arm carried rigidly by said block, a support above said arm, and independent bag holding devices on said support and said receiving arm to support a 25 bag therebetween.

4. A combined bag receiving and delivering device comprising a track, located to one side of and extending longitudinally of a railway, a carriage having supporting rollers revoluble upon said track, said carriage 30 having a pivot knuckle, a block spaced toward the railway from said carriage, a pair

of ears formed integrally with said block and embracing said knuckle, a pivot pin passing through said ears and said knuckle, 35 a bag receiving arm carried rigidly by said block, a bag holding finger formed on said block, a support above said finger and a bag holding device thereon for coaction with said finger to suspend a bag therebetween. 40

5. A device of the character described comprising an upright support located to one side of a railway, an arm projecting from the support toward the railway, a plate projecting longitudinally from the free 45 end of said arm, a transverse loop formed on the upper surface of said plate at its free end, a track extending longitudinally of the railway and having its intermediate portion disposed in said loop, a carriage having rollers contacting with the upper side of the track, and an additional roller contacting with the under side of said plate, and an arm 50 projecting toward the railway from said carriage. 55

In testimony whereof we have hereunto set our hands in presence of two subscribing witnesses.

OLIVER E. J. BRUBAKER.
GEORGE MOTES.
